Primary Examiner — Richard Kearney*Assistant Examiner* — Christina M. Dodson(57) **CLAIM**

The ornamental design for a lantern bracket, as shown and described.

DESCRIPTION

FIG. 1 is a front and top perspective view of a lantern bracket, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in a using position.

The broken lines showing of lanterns and base in FIG. 9 depict environmental structure that form no part of the claimed design.

Other broken lines in the figures illustrate portions of the lantern bracket that form no part of the claimed design.
